UNITED STATES PATENT OFFICE.

WILLIAM F. BROTHERS, OF BROOKLYN, NEW YORK.

BALANCED CABLE-CRANE.

1,245,185.

Specification of Letters Patent. Patented Nov. 6, 1917.

Application filed July 5, 1907, Serial No. 382,254. Renewed April 3, 1917. Serial No. 159,560.

To all whom it may concern:

Be it known that I, WILLIAM F. BROTHERS, a citizen of the United States, residing at Brooklyn, in the county of Kings and State of New York, have invented certain new and useful Improvements in Balanced Cable-Cranes, of which the following is a specification.

The invention relates to improvements in balanced cable cranes and consists essentially in the features hereinafter more fully set forth.

In the following is described in connection with the accompanying drawings one embodiment of the invention, the features thereof being more particularly pointed out hereinafter in the claims.

In the drawings, Figure 1 is a diagrammatic elevation of one form of the invention illustrating one form of the supporting towers and the application thereto of a single or a series of cable-ways adapted to span a large area of water surface and means whereby the movement of the supports and counterweights for said cables are limited and their unit of safety secured; Fig. 2 is an elevation of another form of the invention illustrating the same in connection with a pier, showing the counterweights supported on pontoons, the supporting towers for the cable overhanging the water-way; Fig. 3 is an enlarged side elevation of a cable-way supporting means and counterweights, illustrating part of the structure shown in Fig. 2; and Fig. 4 is an elevation partly in section of a modified form of a differential counterweight.

Similar numerals of reference indicate similar parts throughout the several views. In Fig. 1 of the drawings, 1 indicates a cable suspended between shear legs 2 and 3, said shear legs being in turn supported on rails 4 mounted in foundation 5. Foundation 5 may be counter-sunk beneath the surface of the ground or may be a separate structure. The supporting means shown in the drawings are counter-sunk in the ground. 6, 6 indicate the counterweights suspended from the upper ends of shear legs 2 and 3 by means of cables 7. 8, 8 indicate anchors preferably embedded in the ground and 9 indicates a cable or chain connected with the anchors at one end and fastened at the other end to the respective upper ends of said shear legs 2 and 3. 10 indi-

cates a load carrier adapted to travel in either direction on cable 1. The device as above described is shown as spanning an extended area of water space. Cable 1, illustrated in Fig. 1 of the drawings in full lines, is shown as carrying a definite load at the center of the span, viz. the point of equilibrium and while in this position the tension on the cable is less than when the load is at any other position. The dot and dash line indicated by *a* in Fig. 1, shows the cable in its free position having no load thereon, and while in this position the tension on the cable is at maximum and is much greater than when the cable is in the position shown in the full lines (Fig. 1) because the nearer the cable is to a horizontal line, the greater the tension on the cable, the tension decreasing as the cable departs from the horizontal. The dotted line indicated by *b* (Fig. 1) illustrates the position of the cable when carrying a medium load, which load tends to diminish the tension on the cable as hereinabove described. The object of anchors 8, 8, described as being connected to shear legs 2 and 3 by means of chain 9, is to provide means whereby the inward movement of said shear legs is limited, and hence to secure the safety of any loads put upon the cables.

The device shown in Fig. 2 of the drawings illustrates a pier 11 having constructed thereon a structure 12. 13, 13 indicate supporting base boards having rails 14 mounted thereon adapted to receive wheel or wheels 15 mounted in the lower ends of shear legs 16, 16, the upper ends of said shear legs 16, 16 having a cable or plurality of cables 17 fastened thereto carrying load carriages 18 and 19. Cable 17 carries a telescoping rod 20 adapted to prevent the cable from sagging when either of load carriages 18 or 19 travels toward the center of the span. Shear legs 16, 16 are shown in Fig. 2 as overhanging the water-way. 21 is a pontoon or float having a plurality of counterweights 22 mounted thereon, said counterweights being fastened to the float by means of bolts 22a. 23 indicates a dead-eye or reception hook suitably mounted in counterweight 22 and adapted to engage link 24 in turn adapted to receive a pulley wheel 25 which is adapted to receive an intermediate part of cable 26, comprising a many-reeved fall as shown in Fig. 2, the 110

upper end of said cable 26 engaging pulleys 27 suspended from the upper end of shear legs 16 by means of block and pulley 28 and rod 29. One end of cable 26 passes over 5 intermediate pulleys 30 supported by shear legs 16 and is fastened to a ring or dead-eye 31 mounted in auxiliary counterweight 32, said counterweight being shown as one of 10 a plurality of similar counterweights 32, 34. 33 indicates a series of chains connecting counterweights 32 and 34 together. The weights 32 and 34 in connection with chains 15 33 comprise an adjustable connection to the gravity anchor for the cable 26. The counterweights 32 and 34 furthermore act as differential counterweights in the manner hereinafter described and normally rest upon or may be fastened to counterweights 22 on pontoon or float 21. The object of the 20 pontoon, counterweights 22, and auxiliary counterweights 32 and 34 is to provide a counter-balancing member that will at all times equalize the strain on the load-carrying cable; also to provide means to hold the 25 cable taut thus equalizing all of the strain on said cable in case of a rise or fall in the tide waters wherein a device of the nature as above described is applicable. 35 indicates a boat and as illustrated shows the 30 manner in which the same may be loaded from a pier or any stationary structure built out into a water-way.

The device as shown in Fig. 4 comprises a pontoon or float 36 having mounted thereon 35 in stationary bolts 37 provided with heads 38. 39 is a counterweight in any desired weight and has holes 40 cut therein adapted to receive bolts 37. 41 indicates an opening in said counterweight 39 to permit the passing therethrough of a chain or other suitable connecting link 42 fastened at its lower end in dead-eye 43 in pontoon 36, and at its upper end in cross-head or link 44. Said link 44 is adapted to engage a ring 45 fastened in the lower end of cable 46.

The operation of the devices hereinbefore described is as follows:

In Fig. 1 any load put upon cable 1 is counterbalanced by means of the weight of shear legs 2 and 3 and counterweights 6, 6, the movement of the shear legs being limited by means of anchors 8 and connections 9 whereby the safety of any load put upon said cable is secured, shear legs 2 and 3 being thus permitted to travel but a limited distance. The operation of the structure shown in Figs. 2 and 3 of the drawings is similar to that of the structure of Fig. 1, that is, respecting the means for equalizing 50 the strain put upon cable 17. Any load carried by load carriages 18 and 19 (Fig. 2) is equalized by means of the differential counterweights 22, 32 and 34. In case of an excessive load on said cable 17 counterweights 32 and 34 will be drawn upwardly

to the limit of chain connections 33 and when all of said counterweights are brought into play, will hold the cable 17 taut. If said excessive load requires all of the weight in the plurality of counterweights 32 and 34, counterweights 22 on pontoon or float 21 are utilized as well as the weight of the pontoon or float itself and the resistance offered by the suction tending to be set up between the pontoon or float and the water, the latter obviously acting as a resistant medium. It is further obvious that the reverse of the operation has a similar differential or shock equalizing effect, the water resisting the dropping of the pontoon or float, and the counterweights in their falling and rising gradually arresting or retarding the whipping or lashing motion of the cable caused by letting go the load, thus bringing the cable back to its position of greatest tension without a sudden shock. The combination of all of said counterweights provides a counterweight that will take care of any load put upon the cable and at the same time provides a device for gradually equalizing any strain put upon the cable.

In using the word "tension" in the foregoing specification, I have meant to imply that force in which the tensile strength of the cable comes into play. In the form of device which I have described the tension is greatest when the deflection of the cable is least and the tension is least when the deflection of the cable is greatest.

It is obvious that the forms of the invention as herein shown and described may be widely varied without departing from the spirit of the invention.

What I claim and desire to secure by Letters Patent of the United States is:

1. A device of the character described including a cable, supports therefor adapted to oscillate from the base with variations of the load upon the cable, means carried by said cable adapted to prevent sagging thereof, floats, counterweights carried by said supports and resting on said floats and connections between said supports and floats adapted to counter-balance a load carried by said cable.

2. A device of the character described including a cable, supports therefor, means carried by said cable adapted to prevent sagging thereof, a float, connections between said cable supports and float, counterweights carried thereby and auxiliary counterweights associated therewith adapted to counter-balance the load carried by said cable.

3. A device of the character described including a cable, supports therefor, means carried by said cable adapted to prevent sagging thereof, floats, connections between said cable supports and floats, primary counterweights carried thereby, secondary

counterweights associated therewith and connections between said primary and secondary counterweights.

4. A device of the character described including a support, a cable and a counterweight comprising a float having mounted thereon a plurality of counterweights, a pulley fastened to one of said counterweights, a pulley mounted on the upper end of said cable support, a continuous connection between the respective pulleys and a plurality of secondary counterweights, and means for connecting said plurality of secondary counterweights together.

15 5. A device of the character described including a counterweight comprising a float, a primary counterweight mounted thereon, a secondary counterweight associated therewith, means for limiting the movement of 20 said secondary counterweight and means for connecting said primary and said secondary counterweights together.

6. In a device of the character described the combination with the shear legs, of a 25 gravity anchor, and a many reeved fall for suspending said anchor from said shear legs, one end of the line of the fall being connected to the shear legs and the other to an adjustable connection on the anchor.

30 7. In a device of the character described the combination with the shear legs, of a gravity anchor, a plurality of weights carried by said anchor and loosely connected together, and a many reeved fall for suspending said anchor from said shear legs, one end 35 of the line of the fall being connected to the shear legs and the other to said weights.

8. In an apparatus of the character described, a suspended cable, supports therefor, at least one of said supports being capa-

ble of yielding at its base with variations of the load upon the cable, and means associated with said cable and its supports for equalizing the strain upon said cable.

45 9. In an apparatus of the character described, a suspended cable, supports therefor, a counterweight depending from at least one of said supports, and means coöperating with said counterweight to resist the rising and falling thereof.

50 10. In an apparatus of the character described, a suspended cable, supports therefor, a counterweight for said cable and means resisting the rising and falling of 55 said counterweight.

11. In an apparatus of the character described, a suspended cable, supports therefor, at least one of said supports being movable about its base, and means for automatically varying the tension on the cable.

60 12. In an apparatus of the character described, a suspended cable, supports therefor, at least one of said supports being movable about its base, and means for retarding the cable in its movement to assume the position of no load.

65 13. In an apparatus of the character described, a suspended cable, supports therefor, at least one of said supports being movable about its base, and means for varying 70 the tension on the cable by retarding the vertical movement thereof.

In testimony whereof I have hereunto signed my name in the presence of two subscribing witnesses.

WILLIAM F. BROTHERS.
